UNITED STATES PATENT OFFICE

ENOCH PROUTY, OF BOSCOBEL, WISCONSIN.

PRINTING-PRESS.

SPECIFICATION forming part of Letters Patent No. 249,989, dated November 22, 1881.

Application filed August 12, 1881. (No model.)

To all whom it may concern:

Be it known that I, ENOCH PROUTY, of Bos-
cobel, in the county of Grant and State of Wis-
consin, have invented certain new and useful
5 Improvements in Printing-Presses, of which
the following is a specification, reference be-
ing had to the accompanying drawings.

My improvements relate to the kind of print-
ing-press known as the "Prouty" press, shown
10 in my United States Letters Patent No. 206,826,
of August 6, 1878, and designed to be adapted
for a great variety of work, and for printing
large or small sheets, from the size of a card
to that of a poster, with equal facility.

15 In general character my improved press is
similar to that of my said patent—that is to
say, I have a main frame, upon which a rotat-
ing cylinder (to which the paper to be printed
is fed) is caused to reciprocate by suitable
20 mechanism over an adjustable type-bed, which
is raised and lowered at the proper times to
make the impression, and then to get out of
the way for the return of the cylinder. I also
have an ink-fountain and reciprocating inking-
25 rollers for inking the type, &c.; but in my new
press I provide improved means for gripping the
paper, improved means for guiding and secur-
ing the cylinder during the reciprocation, im-
proved means for raising and lowering the
30 type-bed, improved means for securing the
blanket to the cylinder, and improved means
for delivering the printed sheets, whereby I
dispense with tapes and fliers, all of which I
will now proceed to describe in detail by ref-
35 erence to the letters on the accompanying
drawings, and then to specify succinctly in my
claims.

Figure 1 is a perspective view of my im-
proved press, showing the parts in position,
40 with the cylinder about midway over the type-
bed. Fig. 2 is an opposite-side elevation of
the same, partly in section. Fig. 3 is a trans-
verse section through the main frame, showing
a face view of the cylinder and one end of the
45 type-bed. Fig. 4 is a section through the cyl-
inder on line 44 of Fig. 3; and Fig. 4^a is a sim-
ilar view, showing the grippers in reversed
position. Fig. 5 is an enlarged section of a part
of the cylinder shown in Fig. 4, for better illus-
50 tration. Fig. 6 is a transverse section of the
cylinder on the line 66 of Fig. 3. Fig. 7 is a

longitudinal section of the cylinder on the lines
77 of Figs. 3 and 6. Fig. 8 is a transverse sec-
tion of the inking-fountain on the line 88 of
Fig. 9; and Fig. 9 is a side elevation of the 55
same, partly in section.

A indicates the main frame, provided with
strong side rails, B, for the support of the re-
ciprocating parts. At one end of the frame is
placed at suitable elevation the usual inclined
feed-table, C, upon which the blank sheets to
be printed are laid ready to be seized, one at a
time, by the cylinder D. This cylinder is re-
ciprocated by carriages, which move in ways
along the rails B and carry with them the ink-
ing-rollers. The ink-fountain E is located up-
on the same end of the frame with the feed-
table C, and underneath that table. The re-
ciprocating mechanism consists of the main
driving-wheel F, the pitman-rod G, the rock-
shaft H, the levers I, the links K, the arm L,
and the rod M, and their minor connections;
but I do not confine myself to this particular
reciprocating mechanism, as it may be varied.

From this general outline of the organiza-
tion of the parts it will be understood that the
sheets upon the feed-table are seized, one at a
time, by the grippers of the cylinder, wound
around it, and carried over the printing-bed
and printed, and then released and dropped
away. When the type is inked by the rolls
the return reciprocation is made, and the op-
eration thus continued indefinitely.

Referring, now, more particularly to the de-
tails of the parts constituting my improve-
ments and their operation—

First. As to my improved gripping mech-
anism, N indicates a lug, which projects from the
longitudinal cylinder-opening O out close to
one end of the cylinder. This lug by its shoul-
ders O' is secured to two slide-rods, P, which
pass through the yoke Q and straddle the cyl-
inder-shaft R, and are surrounded by the coil-
springs S, which tend to press the lug outward.
The lug N is connected with a short crank, T,
90 by means of a pin, U, working in an elongated
slot, V, in the crank, and the latter is secured
to a rock-shaft, W, from which project the gripp-
ers X. In suitable positions upon each end of
the frame are the projecting arms or cams Y,
95 for the purpose of striking and depressing the
lug N as the cylinder moves up to the table to

receive a blank sheet and as it nears the end of its opposite movement to deposit a printed sheet. As the lug *N* is depressed, the crank *T* causes the rock-shaft *W* to rock, which operates the grippers in one case to gripe a blank sheet and in the other to release a printed sheet. As soon as the lug *N* is withdrawn from the pressure of the cams *Y*, it is thrown out by the springs *S*, and the grippers assume the position 5 of gripping after a sheet has been fed, and the open or releasing position after a sheet has been printed, so as to release the printed sheet and be ready to receive a blank sheet. This movement is owing to the fact that the cams *Y* strike 10 the lug *N* from opposite sides and tend to press it not only inward, but also to push it or tilt it a little in opposite directions, and the elongation of the crank-slot *V* permits the lug and its supporting-frame to tilt, so that in one case 15 20 the lug is sprung out by the springs *S* on one side of the rock-shaft *W* and then on the other alternately, thus opening or closing the grippers, as above explained. This movement is well illustrated in Figs. 4, 4^a.

25 Second. As to my improved means for firmly and steadily carrying the cylinder and inking-rollers in their reciprocations over the type-bed, *a* indicates outward projections from the sides of the rails *B*, having grooves *b* underneath them. *c* indicates carriages, provided with friction-rollers, which run in the overhanging grooves *b*. These carriages are provided with tubular sockets *d*, the lower projections of which bear against the outside flanges of the 30 rails *B* at the points *e*. Within these sockets are bearing-posts *f*, made adjustable vertically within the sockets by means of the check-nuts *g*. The ends of the cylinder-shaft are mounted in suitable bearings at the tops of the bearing- 35 40 posts. The frame of inking-rollers *h* is connected to the carriages by means of a bracket, *i*, or in any suitable manner, so as to reciprocate with the cylinder. By means of the check-nuts *g* the carriages can be drawn up so that 45 50 their friction-rollers will bear against the bottoms of the grooves *b*, while the cylinder bears firmly upon its tracks *j* on the upper surfaces of the rails. Thus a strong and firm guide and support are formed for the cylinder during its 55 60 reciprocations, preventing its being raised, and insuring its movement to and fro always exactly in the same plane by the reciprocating mechanism. I provide gear-wheels *k* on opposite ends of the cylinder, and rack-bars *l* upon the rails, not so much for the purpose of giving rotary motion to the cylinder as to prevent any liability to slip when in operation.

Third. As to my improved means for raising and lowering the type-bed, *m* indicates two rock-shafts, supported upon brackets *n* underneath the rails *B*. Passing through these rock-shafts are four screw-posts, *o*, adjustable vertically by means of the check-nuts *p*. These screw-posts have large semicircular caps at their tops, 65 which fit in correspondingly-shaped sockets in the bottom of the type-bed. Projecting

downward from one of the rock-shafts is a lug, *q*, slotted at its lower end in two places for the passage of spring buffer-rods *M* and *r*. The operation of these parts for raising and lowering the type-bed is as follows: In the first place, the check-nuts and screw-posts serve to accurately adjust the type-bed in the true position for printing. Supposing the type-bed to be thus adjusted, the gearing and connections 70 75 are such and the movements of the parts are so timed that when the cylinder comes to position to take a blank sheet of paper the rod *M* has passed forward through its slot in the lug *q*, so that its spring-buffer *s* strikes the lug *q* and pushes it to a perpendicular position. This operates both of the rock-shafts and carries the screw-posts which support the type-bed also to a perpendicular position and elevates the type-bed, so that the cylinder, as it 80 85 moves away from the feed-table with the blank sheet of paper, will impinge against the type and print the sheet, and immediately afterward the inking-rollers will freshly ink the type. After the printing has been done, and 90 95 when the cylinder has nearly reached the delivery end of the press, the collar *t* upon the end of the rod *M* will strike the opposite side of the lug *q*, throw it out of perpendicular, and operate the rock-shafts and screw-posts so as to lower the type-bed and permit the cylinder 100 to pass back for a fresh sheet without striking the type. The spring-buffer *u* upon the rod *r* is merely for the purpose of preventing shock and easing the dropping of the bed.

Fourth. As to my improved means for securing the blanket to the cylinder, *v* indicates a bar extending nearly the whole length of the cylinder in its interior on the margin of the longitudinal griper-opening. This bar is provided 105 with small brads, about four inches apart, which project into corresponding holes *w* in the cylinder; or the brads may be set in the cylinder to project inward, and the holes may be made in the bar to receive them. Passing through 110 the wall of the cylinder, near each end, are two screws, *x*, which enter the bar *v* and serve to hold it in place. On the side of this bar is another bar, *y*, secured in place by the clamp-screws *z*. The purpose of this mechanism is 115 to secure one margin of the blanket and tympan, as clearly illustrated in Fig. 6, where it will be seen the brads are set through the edge of the blanket, which is then clamped securely by means of the screws *x* and bar *v*, and then 120 the blanket is drawn outward around the cylinder. The tympan is secured between the two bars and clamped by the screws *z*, and drawn around the cylinder in like manner over the blanket. The blanket and tympan, being 125 wound firmly around the cylinder to the opposite side of the griper-opening, are drawn into the interior of the cylinder and hooked onto a row of brads, *a*², projecting inwardly from a bar, *b*². This bar is adjustable radially by 130 means of screws *c*² passing through it and entering the cylinder-shaft, as clearly shown in

Figs. 6 and 7, whereby the blanket and tympan may be drawn tight, as desired.

I am aware that it is not new, broadly, to tighten a blanket upon a cylinder by the use of a screw projecting radially from the cylinder-axis, and I do not claim that, broadly. My claims are limited to the improvements in the structure of the blanket securing and tightening parts, as above described, when arranged and combined as set forth.

Fifth. As to means for inking, which I show but do not claim, d^2 indicates an ink-receptacle, having the ordinary ink-roller, e^2 , revolving in the ink, and knife f^2 . g^2 indicates set-screws passing through the plate h^2 and engaging with the knife so as to positively control its movement upward as well as downward. For this purpose the lower ends of the screws are cut away or shouldered down to small pins or journal pins i^2 , which pass loosely through the knife and receive upon their lower ends collars or washers, which are held in place by riveting the ends of the pins against them. The result is that the screws will turn freely to raise or lower the knife positively and regulate the amount of ink upon the upper part of the roller.

Sixth. Referring to my improved means for delivering the printed sheets, I provide a receptacle between the ends of the rails, and beyond the type-bed, with a bottom or table, k^2 , for receiving the printed sheets from the cylinder. When short sheets are to be printed I provide a lug, l^2 , which I secure by means of a screw in the proper position upon one of the rails B , as shown in Fig. 2, to be struck by the lug N at the proper time to release the grippers and drop the sheet. This lug l^2 , I remove when longer sheets are to be printed. Thus I deliver the sheets, whether long or short, over each other, one at a time, without the aid of tapes or fliers.

Having thus described my invention, what I claim as new, and desire to secure by Letters Patent, is—

1. The combination, with the cylinder and cylinder-shaft, of the lug N , the reciprocating frame supporting the lug and provided with springs S , the slotted crank T , the rock-shaft W , and the grippers, substantially as and for the purpose set forth. 45

2. The combination of the rails B , provided with the projections and grooves $a b$, the carriages c , provided with friction-rollers running in the overhanging grooves b , the tubular sockets d , bearing against the flanges of the rails at the points e , and the adjustable bearing-posts f , substantially as and for the purpose specified. 50 55

3. The combination, with the type-bed, of the rock-shafts m , the adjustable screw-posts o , the slotted lug q , and the spring buffer-rods $M r$, substantially as and for the purpose specified. 60

4. The combination, with the cylinder, of the bars v and y , the blanket-securing brads, and the screws x and z , substantially as and for the purpose specified. 65

5. The combination, with the cylinder and its axis, of the adjustable bar b^2 , its brads, and the screws c^2 , directly entering the axis, substantially as and for the purpose specified. 70

6. The combination of the adjustable and removable lug i^2 with the rail B and the lug N upon the cylinder, whereby the printing and delivering of short sheets of variable length is provided for, substantially as set forth. 75

7. The combination, with the cylinder, the printing-bed, and the rails, of the receptacle between the ends of the rails and the table or bottom k^2 , for receiving the printed sheets directly from the cylinder, substantially as described. 80

In testimony whereof I have hereunto subscribed my name.

ENOCH PROUTY.
